UNITED STATES PATENT OFFICE.

JAMES L. MCQUARRIE, OF CHICAGO, ILLINOIS, ASSIGNOR TO THE WESTERN ELECTRIC COMPANY, OF SAME PLACE.

AUTOMATIC SIGNALING SYSTEM FOR TELEPHONE-EXCHANGES.

SPECIFICATION forming part of Letters Patent No. 683,569, dated October 1, 1901.

Application filed January 26, 1901. Serial No. 44,906. (No model.)

To all whom it may concern:

Be it known that I, JAMES L. MCQUARRIE, a citizen of the United States, residing at Chicago, in the county of Cook and State of Illinois, have invented a certain new and useful Improvement in Automatic Signaling Systems for Telephone-Exchanges, (Case No. 13,) of which the following is a full, clear, concise, and exact description.

My invention relates to a telephone-exchange system, and concerns more particularly the operator's central-office apparatus for making connections between two telephone-lines, my object being to substitute automatic devices for doing a share of the work which has hitherto been done personally by the operator, and so to economize the operator's time and enable her to handle a much larger number of connections than has hitherto been possible.

With telephone-exchange systems at present in use the operator finds it necessary to ring the called party a definite number of times or a definite length of time, and if no response is had she must connect her telephone with the calling-line and report to the calling subscriber that no answer has been made to her signal. Usually the calling party asks that the subscriber wanted be rung again, and this requires the operator's further attention and time and uses her telephone. The present invention is for the purpose of relieving her of this work by providing a contrivance for automatically ringing the subscriber a definite length of time and then automatically reporting to the calling subscriber that no response is obtained from the called station, the only work required of the operator being the insertion of the calling-plug in the jack of the called line.

The invention may be generally described as comprising a source of peculiar or characteristic signaling-current, (which may be a phonograph-transmitter, a musical-tone-producing transmitter, or the like,) a switch for connecting the same with the calling-line, a time device operated or set in operation during the application of ringing-current to the called line, and means controlled by the time device for actuating said switch. In the preferred embodiment of my invention the ring-

ing-current is periodically interrupted, and an electromagnetic step-by-step device responsive to the intermittently-applied ringing-current advances a predetermined number of steps and then actuates a switch which disconnects the ringing-current from the called line and connects the peculiar signaling-current with the calling-line. The calling subscriber listening in his telephone thus hears after a given time either spoken words from a phonograph, such as "They don't answer," or a peculiar hum or tone, which he recognizes as meaning that the called party has not responded. He will then hang up his telephone, and the usual supervisory signal-lamp at the central office will be lighted, giving the operator the signal to disconnect.

The apparatus of my invention will be useful either at a trunking-board or "B position," where calls are received over trunk-lines from distant boards, or at an answering-board or "A operator's position," where the call comes directly from the subscriber.

I will describe my invention particularly by reference to the accompanying drawing, which is a diagram illustrating two telephone-lines extending from a substation to a central office, with the operator's apparatus for connecting the lines, equipped with the signaling apparatus of my invention, and the features which I regard as new will be pointed out in the appended claims.

The two telephone-lines illustrated, extending from substations A and B to the central office C, are equipped with the usual substation and central-office apparatus, the system being of a well-known type, in which a central source of current is connected with all the lines and each line is provided with a line-relay controlling a subsidiary signal at the central office, responsive to the flow of current in the line, which is determined by the telephone-switch at the substation. The central source of current and the line-relay of each line are connected with such line by way of the back contacts of a cut-off relay a. The magnet of the cut-off relay is included in a ground branch from the test-rings or third contacts of the multiple spring-jacks b of the line.

The apparatus of my invention is intended

more particularly for application to the operator's plug-circuit, as shown in the diagram. The plug-circuit, generally considered, is of the usual type for systems of the character 5 described, and consists of an answering-plug *c* and a calling-plug *d*, the tip and ring contacts of each plug being united with the corresponding contacts of its mate by link conductors 1 2 of the plug-circuit, with a repeating-coil interposed in said link conductors and a central battery *g* in a bridge of said link conductors between the windings of the repeating-coil. A supervisory relay-magnet *e* is associated with the answering-plug and 10 connected in the circuit of the conductor 2 between the central battery *g* and said answering-plug, and similarly a supervisory relay-magnet *f* is included in the portion of conductor 2 leading from the battery to the calling-plug *d*. One pole of the battery *g* is grounded, and the third contacts of the plugs *c* and *d*, which are adapted to engage the test-rings of the jacks, are connected with the free pole of said battery by conductors 3 4, 15 respectively, which include the subsidiary signal-lamps *c'* *d'* and resistances *c*² *d*². The conductor 2 of the plug-circuit between the battery *g* and the calling-plug is in the normal or idle position of the plugs interrupted 20 at the contacts of a relay *h*, the end leading to the ring-contact of the plug being connected to the armature *h'* of said relay and the other end leading to the battery being connected to the front contact of said armature. The relay *h* has two windings. One of 25 said windings *h*² is included in a shunt about the signal-lamp *d'*, which shunt includes and is controlled by the armature and front contact of the supervisory relay *f*, and 30 the other winding *h*³ is included in a conductor 6, which is connected in parallel or shunt with the resistance *d*² and includes and is controlled by the armature *h*⁴ and its front contact of the relay *h* itself. The conductor 35 2, leading to the calling-plug, is normally connected by way of the back contact of relay-armature *h'* and a conductor 7, including certain other apparatus, presently to be described, with the contact-plate *i'* of a continuously-rotating commutator or interrupter *i*. The contact-plate *i'* takes up half the periphery of the commutator and the other half is of insulating material. Two contact-brushes 40 *i*² *i*³ bear upon opposite sides of the commutator, one of said brushes being connected to a grounded battery *k* and the other being connected to a grounded generator of ringing-current *k'*. The conductor 7 includes the winding of a magnet *l*, which controls a step-by-step mechanism, hereinafter to be described, and includes and is controlled by a switch-lever *m*² and its front contact, said lever being operated by the step-by-step mechanism aforesaid. A cam *m* is mounted upon 45 a rotatable shaft *n*, said cam being circular except for two projections or lugs *m'* *m*' at diametrically opposite points upon its periph-

ery. The switch-lever *m*² and a similar switch-lever *m*³ rest upon opposite sides of the periphery of the cam *m*, the ends of said levers being diametrically opposite one another and being yieldingly held down to the surface of the cam by springs. The switch-lever *m*² normally rests against its contact-point, which is connected to the interrupter or commutator 50 *i*, and is separated from said contact-point when the switch-lever rides up upon one of the lugs *m'* of the cam. The other switch-lever *m*³ has a contact-point from which it is normally separated, but with which it engages when moved by one of the lugs *m'* of the cam. This contact-point is connected to the limb *l* of the plug-circuit between the battery *g* and the calling-plug, and the lever *m*³ is connected to a grounded source *s* of specialized current, such as a phonograph-transmitter or an interrupter which will produce a distinctive hum or tone. 55

The shaft *n*, which carries the cam *m*, is mounted to rotate in bearings and carries a ratchet-wheel *o*. A spiral spring *n'*, encircling the shaft, tends to keep the same in the position illustrated—that is, with the lugs *m* *m'* abutting against the ends of the levers *m*² *m*³. Two pawls *p* *p*' engage the ratchet-wheel *o* upon opposite sides. One of these pawls *p* is attached to the armature *l*' of the electromagnet *l* and is adapted to be pressed against the ratchet-wheel *o* by a spring *q*², carried by the armature *q'* of an electromagnet *q*. When the magnet *l* attracts its armature, the ratchet-wheel will therefore be rotated one step. The other pawl *p* is carried by a flat-spring extension of another armature *q*³ of the magnet *q* and is adapted merely to hold the ratchet-wheel in the positions to which it may be advanced by the other pawl worked by the magnet *l*. When the magnet *q* is deenergized, its armatures fall back, thus removing the pawls *p* *p*' from engagement with the ratchet, whereupon the shaft *n* being released is rotated back to its original position. The magnet *q* is included in a shunt 8 about the supervisory lamp *c'* of the answering-plug and is controlled by the armature of the supervisory relay *e*, which is responsive to the flow of current in the calling-line. The armature *q'* of relay *q* and a back contact for said armature control a shunt-path 9 about the armature *h*⁴ and its front contact—in other words, the contacts controlled by armatures *h*⁴ and *q'* are in multiple, and the closure of either completes the circuit through the retaining-winding *h*³ of magnet *h*. 115 120 125

The operation of the system is as follows: Assuming that a call has been transmitted from substation A in the usual manner and answered by the operator inserting her plug in the spring-jack, connecting her telephone in circuit and ascertaining the number of the subscriber wanted, after making the usual "busy test" the operator simply inserts the calling-plug *d* in the spring-jack of the line 130

with which connection is desired. This is all the work that is required of her until the signal is made to take down the connection. When the calling-plug is inserted, the 5 called-party's telephone being on its hook, the supervisory relay f is inert. Consequently magnet h is also inert, and the ring of the calling-plug is thus connected, by way of armature h' and its back-contact winding of 10 magnet l and switch-lever m^2 and its normal resting-contact, with the contact-segment i' of the commutator or interrupter i . As the commutator rotates ringing-current is intermittently applied to the line, a steady current 15 being substituted for the ringing-current during the intermissions. The magnet l is responsive to the alternating ringing-current; but the magnet of the supervisory relay f is not. The telephone-receiver being on the 20 hook at the called station, no return-path is provided for the steady current, so that neither of the magnets just mentioned is affected by such current until the subscriber has answered the call by removing his telephone from the hook, and so closing the circuit. 25 At each application of ringing-current to the line by the commutator i , therefore, the magnet l will be excited and will attract its armature, and in the intermissions the magnet 30 becomes inert and allows its armature to fall back. The magnet q at this time is excited, because the shunt-circuit controlled by the supervisory relay e of the calling-line is closed, (the calling-subscriber's telephone being off 35 the hook,) so that the pawls p p' are yieldingly held against the ratchet-wheel o . Each time the magnet l draws up its armature, therefore, the shaft n will be held by the pawl p in the position to which it is advanced. If 40 the called subscriber does not respond, the commutator will continue to apply the ringing-current intermittently to his line until the step-by-step mechanism has advanced the cam m sufficiently to engage the lugs m' m' 45 with the switch-levers m^2 m^3 . As the switch-lever m^2 rides up on one of the lugs m' of the cam it breaks the circuit of conductor 7, leading to the commutator and the sources of current connected therewith, and simultaneously 50 the switch-lever m^3 is pushed into engagement with its outer contact. The effect, therefore, is to stop the application of ringing-current to the called line and to connect the source of peculiar or specialized current s with the 55 conductor l of the plug-circuit. Current from the source s thus flows to ground through a winding of the repeating-coil, whereby a corresponding current is induced in the other windings of the repeating-coil, which flows 60 back to the calling-station and produces an audible signal in the telephone of the subscriber who is listening for a response to his call. This signal may be either spoken words from a phonograph or a hum or tone or any 65 other audible signal which the calling subscriber will recognize as meaning that no response is had from the called station. The

calling party upon hearing the special "don't-answer" signal knows that it will be of no use to signal the called party any longer and 70 replaces his telephone on its hook, thus bringing about the illumination of his supervisory lamp c' . Since the supervisory lamp d' of the called party is still lighted, the illumination of both lamps constitutes a signal to the 75 operator to disconnect. At the same time the magnet q is deprived of current by the opening of the shunt 8 and allows its armature to fall back, thus releasing the ratchet-wheel o . The shaft n is therefore returned 80 to its initial position by the coiled spring n' . The armature q' in falling back closes the circuit through the winding h^3 of magnet h , which in drawing up its armatures permanently cuts off the ringing-current from the called 85 line. In ordinary cases, however, the called subscriber will answer and in taking his telephone for use will close a bridge of his line-circuit, whereupon the supervisory relay f at the central office will respond to the flow of 90 current in the line and close the shunt 5, which includes the winding h^2 of magnet h . This magnet in drawing up its armatures cuts off the ringing-current and establishes the talking-circuit through the repeating-coil. Circuit 95 through the retaining-winding h^3 is also closed by armature h^4 , so that the magnet h is now independent of the telephone-switch at the called station and maintains the ordinary talking-circuit connections as long as 100 the plug remains in the spring-jack.

It will be apparent that my invention is capable of being applied to the receiving end of a trunk-line to signal back to the answering-board, and where in the claims I use the term 105 "calling-line" I do not mean to restrict myself to a subscriber's line. In fact, my invention is capable of application to telephone systems of various kinds, and the arrangement shown in the drawings may be modified 110 within comparatively wide limits and still make use of the new ideas which I have herein set forth. I do not therefore wish to be understood as limiting myself to the precise apparatus and circuits illustrated; but, 115

Having described the preferred embodiment of my invention, I claim as new, and desire to secure by Letters Patent, the following:

1. The combination with a calling and a called telephone-line and means at a central 120 office for uniting them, of an automatic ringing device at the central office for sending signaling-current over the called line, a source of distinctive signaling-current, a switch for connecting the same with the calling-line, a 125 time device set in operation simultaneously with the automatic ringing device, and means controlled by said time device for actuating said switch, whereby the calling party is automatically notified when the called station 130 has been signaled a given time, substantially as set forth.

2. The combination with a calling and a called telephone-line and means at a central

- office for uniting them, of an automatic ringing device at the central office for signaling the called station, a source of peculiar or characteristic signaling-current, a switch for disconnecting the ringing-current from the called line and applying the peculiar signaling-current to the calling-line, and an electrical device operated by the flow of ringing-current in the called line, for bringing about the operation of said switch, whereby ringing-current is automatically applied to the called line for a given time and then stopped, and a signal transmitted to the calling-station, substantially as set forth.
- 15 3. The combination with a calling and a called line, and means at a central office for uniting them, of a source of ringing-current and a ringing device at the central office for connecting the same with the called line, means controlled through the agency of a switch at the called station for disconnecting the ringing-current, a time device set in operation when ringing-current is applied to the called line, a source of characteristic signaling-current and a switch for connecting the same with the calling-line, controlled by said time device, whereby the called party is automatically signaled for a definite time and, upon his failure to respond, a report to that effect automatically made to the calling party, substantially as set forth.
4. The combination with a telephone-line extending to a central office, and means for connecting it with a second or called line, of a source of ringing-current and means for connecting the same with the called line to signal the called party, means at the central office, under the electrical control of the called party for disconnecting the signaling-current from the line, a source of characteristic signaling-current, and a switch for applying the same to the first-mentioned or calling line, and a time device for operating said switch, said time device being controlled by the flow of ringing-current in the called line, substantially as set forth.
5. The combination with a calling and a called telephone-line, and means at a central office for uniting them, of a source of ringing-current and means for automatically applying the same to the called line, means at the central office, under the electrical control of a switch at the called station, for disconnecting the source of ringing-current, a

source of peculiar or characteristic signaling-current, and an automatic switch for applying the same to the calling-line, an automatic interrupter for intermittently disconnecting the ringing-current from the called line, and a step-by-step device operated by the intermittent flow of ringing-current, controlling said automatic switch, whereby the called party is automatically signaled for a given time, and a signal then transmitted to the calling party indicating that there has been no response, substantially as set forth.

6. The combination with a calling and a called telephone-line and means at a central office for uniting them, of a source of ringing-current and an automatic ringing device for applying the same to the called line, means controlled through the agency of a switch at the called station for disconnecting the source of ringing-current, a source of current connected with the calling-line, means at the substation of the calling-line for determining the flow of current therein, and electromagnetic mechanism controlled by the flow of current in the calling-line, for disconnecting the ringing-current from the called line, substantially as set forth.

7. The combination with a calling and a called telephone-line and means at a central office for uniting them, of a source of ringing-current and means for automatically applying the same to the called line, means at the central office under the electrical control of a switch at the called station, for stopping the flow of the ringing-current, a source of peculiar or characteristic signaling-current, a switch for applying the same to the calling-line and disconnecting the ringing-current from the called line, an instrument in the calling-line responsive to such peculiar signaling-current, a rotatable cam for actuating the switch last mentioned, a device for intermittently interrupting the flow of ringing-current in the called line, and an electromagnetic step-by-step device responsive to the intermittently-interrupted ringing-current, for controlling the rotation of the aforesaid cam, substantially as set forth.

In witness whereof I hereunto subscribe my name this 4th day of December, A. D. 1900.
